UNITED STATES PATENT OFFICE.

MICHEAL DAVID SHEEHY, OF KITCHENER, ONTARIO, CANADA.

ROTARY OIL BURNER.

Application filed September 11, 1926. Serial No. 134,859.

My invention relates to improvements in rotary oil burners, and the object of the invention is first to provide means for atomizing the oil to a maximum extent, second to provide simple means incorporated in the burner structure for supplying a forced draft of air to the oil as it is atomized, and third to provide a rotary burner which may be driven with a minimum amount of power, and it consists essentially of the arrangement and construction of parts as herein after more particularly explained.

Fig. 1 is a side elevation of the complete assembly showing the fuel atomizing and burning apparatus in section.

Fig. 2 is a plan view of the fuel atomizing and burning apparatus.

Fig. 3 is a perspective view of one of the rotary members showing it in an inverted position, and,

Fig. 4 is a fragmentary perspective view of one of the supports and a portion of the coacting rotary atomizing member mounted thereon.

In the drawing like characters of reference indicate corresponding parts in each figure.

2 is a tubular standard having a hollow base 1 of cone shaped formation and formed integral therewith. The tubular standard 2 and base 1 form a housing for the oil conduit hereinafter described. The tubular standard 2 is provided at its lower end with an external annular shoulder 1^x and at its upper end with an internal annular shoulder 1°. 3 is a tubular shaft forming an oil conduit extending upwardly through the centre of the standard 2 and base 1 and adapted to rotate therein. The lower end of the shaft 3 is supported by and mounted within a footstep bearing 4° as indicated by dotted lines in Figure 1, such bearing being suitably packed to prevent any leakage of oil therefrom. 5 and 6 are a pair of ball races respectively situated intermediately of the height of and at the top of the shaft 3 and constituting bearings therefor, the bearing 6 being mounted on the shoulder 1° so as to form a hanger support for the shaft 3. The upper end of the shaft 3 extends upwardly beyond the bearing 6 and is provided at its upper end with angularly upwardly inclined radially extending oil emitting nozzles 7.

8 is a rotatable vaporizing member in the form of a conically dished plate which is secured centrally to the nozzles 7 so as to

rotate with the shaft 3, and a plurality of radially extending pairs of inner and outer vanes 9 and 10 extending downward from the lower face of the aforesaid plate. 20 60 is a vaporizing member coacting with the member 8 and comprising an annular plate spaced apart and parallel with the plate 8 and provided with upwardly extending vanes 18 and 19. The member 20 is rotatable in an opposite direction to the member 8, the annular paths of the plates 9 and 10 being closely adjacent to the paths of the vanes 18 and 19 extending parallel therewith.

11 is an open ended cylindrical casing spaced apart from and surrounding the standard 2 and plate 8. 13 is an annular member forming a pulley surrounding the bearing 14 mounted on the shoulder 1^x. 12 75 is a plurality of arms mounted on the pulley 13 and inclining outwardly and upwardly therefrom to form a support for the member 11 and curving inwardly at their upper ends to form a support for the member 20. 80 The upper portions 15 of the arms 12 are curved inwardly and downwardly and upon which is mounted the vaporizing member 20, the extreme ends of the portions 15 being mounted upon the outer ring 16 of a ball race 17 surrounding and secured to the upper end of the standard member 2.

The pairs of downwardly extending vanes 9 and 10 are adapted to pass between the upwardly extending vanes 18 and 19 as the vaporizing members 11 and 20 are rotated in opposite directions. The vanes 19 are provided with inwardly extensions 21 adapted to break up any oil passing downwardly towards the shaft 3 and at the same time causing an upwardly auxiliary draft of air across the face of the nozzle 7.

22 is a pulley secured to the shaft 3 in proximity to its lower end for rotating the same and the burner member formed by the plate 8 and vanes 9 and 10. 23 is an electric motor suitably positioned in the vicinity of the burner mechanism being of course exterior to the furnace casing, and 24 is a crossed endless belt connecting the pulley 22 with a pulley 25 secured to the shaft of the motor 23. 26 is a pulley also secured to the shaft of the motor 23 and connected by a belt 27 to the pulley 13 for rotating the member 20 and the vanes 18 and 19 thereof. The driving belts 24 and 27 being wound in opposite directions as above described upon

the pulleys 25 and 26 serve to rotate the atomizing members 11 and 20 in opposite directions.

5 In order to provide a current of air to the oil as it is atomized I provide the following device.

10 28 are blades mounted upon the downwardly inwardly extending portion of each arm 12. These blades are secured to the arms by means of straps 29 which pass around the arms and are adjustably secured to the blades by set screws or any other suitable means. The provision of these straps permits the angularity of the blades to be 15 altered to give the particular volume of air current required.

20 30 is the main oil feed pipe leading from the oil reservoir tank (not shown), such tank can be positioned at any desired elevation to give the required head of oil. The burner end of the oil pipe 30 is suitably connected to the oil conduit bearing 4 so that the oil freely flows from the pipe through the bearing into such conduit and from 25 thence up to the nozzles.

The operation of my device is as follows:

When it is desired to put my burner into 30 operation, oil is permitted to flow from the oil reservoir tank along the oil pipe 30 and through the conduit 3 up to the nozzles 7, the electric circuit connecting with the motor 23 is then closed to start the motor which through the medium of the belts 24 and 27 rotates the plates 8 and casing 11 in opposite 35 directions as before described. As the downwardly extending sets of vanes 9 and 10 are mounted upon the lower face of the cone-shaped disc 8 they will be rotated in one direction together with the oil conduit 3 and 40 attached nozzles 7 and as the casing 11 is supported upon the arms 12 the upper curved ends of which carry the sets of vanes 18 and 19 such vanes will rotate in the opposite direction to the sets of vanes 9 and 10 passing 45 therebetween as before described. The blades 28 carried upon the arms 12 will of course also rotate and create an upward draught of air through the casing 11 which will mingle with the oil vapor ejected from 50 the nozzle 7. When the burner mechanism has been rotated for a short period in order to give the oil an opportunity to freely flow a light is applied to the upper end of the casing 11 when the oil vapor will immediately 55 burst into flame and continue burning as it is ejected.

By the provision of the sets of vanes rotating in the opposite direction to one another it will be readily appreciated that the 60 oil upon passing from the nozzles 7 into the space through which vanes 9 and 10 and oppositely travelling vanes 18 and 19 travel will be broken up and finely atomized before reaching the periphery of the disc 11 where 65 it bursts into flame.

By the provision of ball races at all points of rotation and by the light yet strong construction of my device it will be seen that a motor of comparatively small horse power will only be required to operate the burner 70 and also by making my device of simple and compact construction I have devised an oil burner which can be readily installed in any standard type of furnace without the necessity of making any alterations, furthermore by mounting the plates 28 so that they are capable of adjustment I have devised means whereby the volume of air blast can be altered to suit the supply and consistency of the oil and thus a flame of any desired heat can be obtained. By the use of my particularly efficient means for insuring the complete mechanical vaporization of the oil it will be appreciated that hydrocarbon fuel of any density can be successfully used. 80

What I claim as my invention is:

1. In a rotary oil burner, a rotatable shaft mounted to revolve in suitable bearings, an upper plate carried centrally upon the upper end of the shaft, a lower plate spaced 90 beneath the aforesaid plate and through the open centre of which the aforesaid shaft passes, means for rotating the lower plate in an opposite direction to the upper plate and shaft, and an inner and outer series 95 of vanes carried by each plate and spaced radially apart at a distance equal to the width of the vanes, the vanes of one plate being arranged in intermeshing relation with the vanes of the other plate. 100

2. In a device of the class described, a vaporizer comprising upper and lower annular plates spaced apart and adapted to rotate in opposite directions, and an inner and outer series of vanes extending from 105 each plate and spaced radially apart at a distance equal to the width of the vanes so that the vanes of one plate assume an intermeshing position with the vanes of the other plate. 110

3. In a rotary oil burner, a tubular shaft mounted in suitable bearings and having radial nozzles formed at the upper end of the shaft, an upper plate carried centrally upon the upper end of the shaft, means for rotating the shaft, a lower annular plate spaced beneath the aforesaid plate and through the open centre of which the shaft passes, a revoluble element upon which the annular plate is carried, means for rotating 115 said elements in opposite directions to the shaft, and an inner and outer series of vanes spaced radially apart a distance equal to the width of the vanes and arranged concentrically around the plate. 120

4. In a rotary oil burner, a tubular shaft mounted in suitable bearings and having radial nozzles formed at the upper end of the shaft, an upper plate carried centrally upon the upper end of the shaft, means for 130

- rotating the shaft, a lower annular plate spaced beneath the aforesaid plate and through the open centre of which the shaft passes, a revoluble element upon which the 5 annular plate is carried, means for rotating said elements in opposite directions to the shaft, an inner and outer series of vanes spaced radially apart a distance equal to 25 the width of the vanes and arranged concentrically around the plates, air propelling members carried by the revolving element, and comprising a series of wind vanes, and means for adjusting the angular set of the 30 vanes.
- 10 centrically around the plates, and air propelling members carried by the revolving element.
5. In a rotary oil burner, a tubular shaft mounted in suitable bearings and having 15 radial nozzles formed at the upper end of the shaft, an upper plate carried centrally upon the upper end of the shaft, means for rotating the shaft, a lower annular plate spaced beneath the aforesaid plate and 20 through the open centre of which the shaft passes, a revoluble element upon which the annular plate is carried, means for rotating
- said element in opposite directions to the shaft, an inner and outer series of vanes spaced radially apart a distance equal to 25 the width of the vanes and arranged concentrically around the plates, air propelling members carried by the revolving element, and comprising a series of wind vanes, and means for adjusting the angular set of the 30 vanes.
6. A rotary oil burner comprising a tubular standard, a tubular shaft centrally and revolvably mounted in the standard, a pulley secured to the shaft, a pulley mounted on the standard, an atomizing member driven by the shaft and its pulley in one direction, an atomizing member driven by the pulley of the standard in an opposite direction to the aforesaid member, and wind 40 vanes carried by the pulley of the standard to create an air current surrounding the members of the atomizer.

MICHEAL DAVID SHEEHY.
